UNITED STATES PATENT OFFICE.

SIMEON T. CAST, OF HUNTINGTON, INDIANA.

DESIGN FOR A GATE-HINGE MEMBER.

SPECIFICATION forming part of Design No. 32,694, dated May 22, 1900.

Application filed April 4, 1900. Serial No. 11,532. Term of patent 14 years.

To all whom it may concern:

Be it known that I, SIMEON T. CAST, a citizen of the United States, residing at Huntington, in the county of Huntington and State of Indiana, have invented and produced a new and useful Design for a Gate-Hinge Member, of which the following is a specification.

In the accompanying drawing the figure is a side view of a gate hinge member, showing my new design.

As shown in said drawing, the hinge member consists of a rod, round in cross-section, having its ends bent at right angles to the body portion of the hinge member and said ends pointed at their terminals. The body portion of the hinge member is formed in two sections, the upper one being plain and the lower one having a series of frusto-conical

buttons thereon, said buttons being set at equal distances apart on the rod. The two sections of the hinge are divided by an intermediate loop which extends in the same plane as the terminals of the hinge member, but is of less length than said terminals.

Having thus fully described my invention, what I claim is—

The design for a gate-hinge member, substantially as shown and described.

In testimony whereof I have hereunto set my hand in presence of two subscribing witnesses.

SIMEON T. CAST.
